PIPE TONG

Gird E. Mullinix, San Marino, Calif., assignor to
 Byron Jackson Co., Huntington Park, Calif., a
 corporation of Delaware

Application December 15, 1941, Serial No. 423,011

5 Claims. (Cl. 81—99)

1

This invention relates to pipe tongs, and more particularly to that class of pipe tongs known as tubing tongs. Tubing tongs are hand tongs used in the oil industry for screwing and unscrewing tubing in oil wells, oil gathering lines and refineries. Although tubing tongs will, as a rule, grip but a single size of tubing, they are often used in preference to chain tongs which will accommodate a wide range of sizes. The main reason for the use of tubing tongs in preference to chain tongs is the greater speed and ease of operation of tubing tongs. When making up or breaking out a large number of joints of tubing of the same size, the saving in time warrants the extra investment in a number of tongs for single sizes of tubing. The so-called "open end" or "stab on" type of tubing tong is preferred for speed and ease of operation, but such tongs have heretofore contained one or more objectionable features; such as, slipping on off-size tubing, drooping, falling off the tubing when being passed around, slipping when worn, crimping the tubing under a heavy pull, inability to ratchet, sever die wear or chipping, or too great a weight for a hand tong, etc.

The present invention relates to improvements in tubing tongs of the type shown in Patent No. 2,026,516, issued January 7, 1936, to John D. Chesnut and Richard K. Hertel.

It is an object of the present invention to provide an "open end" tubing tong which has, in addition to the usual operating requirements, a wide range of take-up, even when the tong parts are worn considerably.

Another object is to provide an "open-end" tong which can be ratcheted but which can not be removed from the tubing until the lock has been released manually.

Another object is to provide a "stab on" tong which will not "droop" when placed on vertical tubing.

Another object is to provide means for holding the tong jaw in the open position when the tong is removed from the tubing, said holding means being releasable upon application of the tong to the tubing.

Another object is to provide auxiliary lock releasing means to permit easy removal of the tong from the tubing when the tong is used as a "lay" tong.

Another object is to provide a tubular handle which is both light and strong and which serves as a housing for spring-pressed plunger mechanism.

Another object is to provide a bushing which

2

can be reversed when worn on one side and which can be replaced with various sizes of bushings to accommodate various sizes of pipe.

Another object is to provide a bit which will positively grip the pipe and which remains relatively sharp even when worn down.

Other objects and advantages will be apparent from the following description of a preferred embodiment of my invention.

10 Fig. 1 is an elevational view of the tong head, the handle of the tong being broken away.

Fig. 2 is a plan view, partly in horizontal section through the tong taken on line II—II of Fig. 1, the tong being in the closed position on the tubing.

Fig. 3 is a view similar to Fig. 2, but illustrating the relation of the parts when the tong is open and about to be applied to a piece of tubing.

Fig. 4 shows the position of the locking parts when the tong is applied loosely to a pipe.

Fig. 5 shows the additional lock releasing means with which the tong may be equipped for use as a lay tong.

Referring more particularly to the parts as shown in the drawings, 1 indicates the tong head which comprises a pair of oppositely disposed prongs or forks 2 and 3 which project in the direction of the longitudinal axis of the tong lever 4. In this way, a deep U-shaped socket 5 is formed for receiving the pipe or tubing 6. The prong 2 is preferably bifurcated so that it presents two separate flanges 8, and between these flanges an arcuate jaw 9 is pivotally mounted on a removable bolt or pin 10. This arcuate jaw 9 has an outer extension 11 with a curved guide lip 12 cooperating with the opposite prong 3 in guiding the pipe into the socket, as illustrated in Fig. 3, and beyond this curved lip a die or bit 13 is provided. The bit 13 is retained in place by any suitable means such as cotter keys 17 extending through bosses 1a at the ends of the bit slot 1b and overlying the ends of the bit. The bit is preferably triangular in section and is positioned so that its leading face 1c points to the center of the pipe. This jaw has means for engaging the side of the pipe at two points: at one point the bit 13 engages the side of the pipe, and at another point on the other side of the pivot bolt 10, the other end of the jaw is formed with a flat pad or cheek 14 for engaging the pipe. This pad or cheek 14 is formed on the tail portion 15 of the jaw and is so positioned that the point of contact between the pad and the pipe lies toward the prong 3 from the longitudinal axis of the tong head, and is sufficiently long to contact pipe which

may be as much as $\frac{1}{16}$ inch over or under size on the diameter. The tail portion 15 is bifurcated, forming two fingers 16 and 17 on either side of a recess 18. The finger 17 serves as a stop to limit the opening movement of the jaw 9 by striking against the shoulder 19 in the prong 3 (see Fig. 3). The other finger 16 has its end curved on a short radius, as indicated at 20, to form a cam surface which engages the plunger 35, as will be described later.

Opposite the curved lip 12, the prong 3 terminates in a curved guide lip 21, which cooperates with the lip 12 to guide the tong into position around the pipe or tubing. When the tong is fully applied to the tubing the periphery of the tubing engages the bit 13 and also engages the pad 14, as illustrated in Fig. 2. In addition, the periphery of the pipe at the point E will engage, with the inner face of a slideable bushing 25 mounted on the prong 3. The three points of contact with the pipe, at E, 1c and 14, are distributed around the periphery of the pipe at substantially equal distances. The inner face 26 of the socket 5 is smooth and is disposed at a wedging angle with respect to the pipe. The wedge face 26 is preferably curved on a radius from the center D passing through the center of the pipe and the contact point E. The inner and outer faces 27 and 28, respectively, of the sliding bushing 25, are also formed with curved faces corresponding to the curvature of the socket 5. The center D is determined as follows: a line A—O is drawn through the center of the pipe and the center of the hinge pin 10, to the point of intersection O on the outer periphery of the pipe. A line O—B is drawn from the point O, so that the included angle A—O—B is approximately 11°. An arc C having a radius O—A and a center O is drawn to intersect the line O—B at D. From the point D a line D—E is drawn through the center of the pipe, intersecting the periphery of the pipe at E. An arc F is drawn from the center D with a radius D—E, this arc being the curvature of the bushing 25 and the face of the socket 5. The curvature of the arc F provides a constant wedge angle of approximately 11° with the arc G whose radius is A—O. That is, the angle between the tangents to the circles whose radii are D—E and A—O, at the point of intersection of the circles, is approximately 11°, at all points along the arc F. Obviously, the wedge angle can be somewhat more or less than 11°, but I have found that 11° gives the best condition for gripping and releasing.

The slideable bushing 25 is not essential to the operation of my tong, but with the bushing the tong releases more easily and the wear on the wedge face 26 is greatly reduced because the pressure is distributed over a large area instead of being confined to a mere line contact. Also, thicker or thinner bushings may be substituted for the bushing 25 to accommodate smaller or larger diameter pipe.

The prong 3 is recessed to form a pocket 29 adapted to receive a tail 30 on the under side of the bushing 25. The tail 30 is shorter than the length of the pocket 29 so that it can move back and forth in the pocket about $\frac{1}{16}$ of an inch. The tail is provided with a slot 31 adapted to loosely receive a pin 32, which extends through holes in the prong 3 and retains the bushing 25 slidably in place. The bushing 25 is symmetrical so that it can be reversed when worn on one side.

With the construction described above, when the tong is placed on a piece of pipe and the 75

handle is swung in the direction of the arrow A, the slideable bushing moves to the rear of the slot 31 as the bushing slides around the periphery of the pipe with a wedging action which forces the bit 13 into gripping engagement with the pipe and thus causes the pipe to be turned. A reverse movement of the lever loosens the wedge and permits the tong to let go of the pipe. With the construction shown it is not necessary to reverse the lever manually. As soon as the operator lets go of the lever it will back up of its own accord until the bushing 30 has moved forward in the slot 31, because of the steep 11° wedging angle, thus freeing the tong.

It is desirable that tubing tongs should stay on the pipe while being passed around by the floor crew. In order to keep the tongs on the pipe, I provide a cam plunger 35, which engages the cam face 20 on the pivoted jaw 9. The plunger 35 is urged toward the cam 20 by a coil compression spring 36 which bears against a seat 37 welded or otherwise secured to or formed in the tubular handle 4. The forward end of the plunger 35 is provided with a cam face 38 which engages the cam 20 when the jaw 9 is in the closed position shown in Fig. 2. The purpose of the cam 38 is to hold the tong up to the pipe so that the tong will not droop or slide down the pipe when being passed around. The cam face 38 is made sufficiently long so that it will contact the cam 20 on the jaw 9 in any position of the jaw which may result from the pipe being $\frac{1}{16}$ over or under size. Heretofore it has been customary, in a tong of the general type described herein, to exert the spring force on the pivoted jaw in a substantially tangential direction, whereby substantially the full force of the spring exerts a turning moment on the jaw in closing direction. With such a construction, it is apparent that if the spring is of sufficient strength to hold the tong up to the pipe, so that it will not droop or slide down the pipe while being passed around, it necessarily follows that removal of the tong from the pipe is rendered difficult by the necessity of exerting sufficient manual force to retract the relatively strong spring. In order to overcome this difficulty, I have so arranged the location of the cam face 38 with respect to the direction of sliding movement of the plunger 35, that a relatively light spring will exert sufficient force on the pivoted jaw 9 to hold the tong snugly on the pipe, thus requiring only slight manual effort to release the tong.

Referring to Fig. 2 of the drawing, it will be observed that the cam face 38 on the plunger 35 is disposed at an acute wedge angle of approximately 25° to 30°, with respect to the axis of the plunger. The magnitude of this angle is important only in conjunction with the tangent to the arc of swinging movement of the cam surface on the pivoted jaw, with which it determines the spring force required to hold the tong snugly up to the pipe. I have found it desirable to provide as small a wedge angle as possible, whereby to reduce the spring force to a minimum, but yet avoiding too close an approach to a wedge angle which would cause the wedge to be self-locking. Obviously, a self-locking wedge would render it impossible to ratchet the tong in back-up direction. I have found that a wedge angle of between 25° and 30° is most satisfactory in the present instance, a median value of 27½° being preferable.

I have also found it particularly desirable to so

dispose the plunger 35 that its axis, or line of travel, extends on the inner side of the jaw pivot 10—that is, on the side thereof toward the pipe recess. By this arrangement, as the jaw 9 swings about its pivot 10 in a pipe-releasing or clockwise direction, the cam finger 16 moves downwardly and to the left, as viewed in the drawing. The cam surface 20 on the cam finger is thus caused to slide along the cam surface 38 on the plunger 35, toward the tip 39 of the plunger. This relative movement between the cam surfaces has two desirable effects:

(1) The force exerted by the finger 16 on the plunger is directed more nearly in a direction transverse to the axis of the plunger, instead of along the axis of the plunger. This contributes materially to the reduction in spring pressure required to hold the tong snugly on the pipe.

(2) As viewed in the drawing, the horizontal component of the path of movement of the finger 16 is in a left-hand direction, or opposite to the movement of the plunger, so that these movements are additive. Consequently the distance through which the plunger is required to travel to permit a given arcuate movement of the jaw is considerably less than that which would be required if the plunger axis extended on the outer side of the jaw pivot 10.

It will also be observed, with reference to the drawing, that the wedge angle between the cam faces 20 and 38 is also approximately 25° to 30°. This wedge angle is defined by the cam face 38 and a line drawn tangential to the arc of swinging movement of the finger 16 at the point of contact with the plunger, this line representing the instantaneous direction of movement of the point of contact. It is to be noted, however, that this wedge angle between the cam faces 20 and 38 varies for different angular positions of the jaw, and decreases in value as the point of contact between the cam faces approaches the tip of the plunger. In order to avoid a self-locking wedging condition between the cam faces, the minimum value of the wedge angle should be greater than twice the friction angle of these surfaces. For the range of variation in this wedge angle in the present instance, I have found that a median value of about 27½° is satisfactory.

In order to hold the jaw 9 releasably in the open position, as shown in Fig. 3, I provide the plunger 35 with a surface 39 adapted to press against the cam face 20 and hold the tail 17 of jaw 9 against the stop shoulder 19. When the pipe strikes the pad 14 the cam 20 is moved off of the surface 39, permitting the spring pressed plunger 35 to move to the operating position shown in Fig. 1.

In order to positively lock the tong against inadvertent removal from the pipe, I provide a small flat 41 on the end of the plunger 35 on the face which has the 27½° wedge angle. The face of this flat 41 is substantially parallel to the axis of the plunger. When the tong is around the pipe but not pulled up tight, the cam 20 on jaw 9 contacts the flat 41, as shown in Fig. 4. The flat 41 on the plunger prevents the plunger from being pushed back against the spring 36 and thus locks the jaw 9 against opening movement until the plunger has been retracted manually.

Two separate means for manually retracting the plunger 35 are shown. Either, or both may be used. The plunger is provided with a stem 43 which extends through a guide hole 44 in the spring seat 37. The stem 43 is provided with a

hole to receive a pin 45, which extends laterally through a pair of oppositely disposed slots 46 formed in the tubular handle 4. A sleeve 47 is slidably mounted on the handle 4. The pin 45 extends through holes in the sleeve 47, the end of the pin 45 being riveted or otherwise secured to the sleeve. When the sleeve 47 is pulled back against the pressure of the spring 36, the plunger 35 is retracted until the cam 20 can pass from the position shown in Fig. 2 to the position shown in Fig. 3.

The tubular handle 4 is secured to the tong body 1 by any suitable means, such as welding, as indicated at 48 and 49.

15 A reinforcing tube 50 may be inserted in the tubular handle, if desired, the tube extending from a point inside the body 1 to a point beyond the rear end of slots 46.

If it is desired to use the tong as a "lay" tong, that is, on pipe which is in a horizontal position, 20 as in a ditch or trench, I may provide a second means for retracting the plunger 35, which means is operated from the end of the handle. As shown in Fig. 5, this auxiliary may be accomplished by extending the plunger stem 43 to the end of the handle as indicated at 51. The end of the stem extension 51 is secured to a sleeve 52 by any suitable means, such as a pin 53. The sleeve 52 slides in the handle 4. The sleeve is preferably provided with corrugations 54, the outside diameter of which are no greater than the diameter of the handle, so that a "snipe" (a tubular extension) can be used on the end of the handle when necessary.

30 35 A pipe tong constructed as described above is light in weight but sufficiently strong to break very tight joints. It is easy on the pipe because of the substantially equal distribution of the three contact points, 7c, 14 and E about the pipe. It 40 can be stabbed straight onto the pipe with very little effort. The bit 13 is protected against damage while applying and removing the tong by the action of the releasable locking plunger 35. This minimizes the danger of sparks and increases the life of the bit. Although the tong handle extends directly away from the opening between the jaws, the tong will maintain itself in the horizontal position on a vertical pipe because of the pressure of the spring pressed cam plunger 45 50 against the cam on the pivoted jaw. The tong can not come off the pipe accidentally while being passed around because of the locking flat on the end of the spring pressed plunger. The tong can be used as a lay tong by extending the 55 latch release through to the end of the tubular handle.

It is to be understood that the foregoing description is of a preferred embodiment of my tong and that my invention is not limited to the 60 specific details described, but is of the scope covered by the appended claims.

I claim:

1. A pipe tong comprising a handle and a plurality of relatively constrictable pipe-engaging 65 jaws mounted thereon, means pivotally connecting at least one of the jaw members to the handle so that movement of the handle about its pivot tends to constrict said jaws, and means yieldably maintaining the jaw member which is pivoted to the handle in pipe-engaging position comprising cam means mounted on the handle and having a cam surface wedgingly engaging a cooperating surface on said pivoted jaw member, the effective wedge angle between the cam surface on the cam 70 means and the cooperating surface on said piv- 75 ing member being substantially greater than the friction angle between the cam surface and the cooperating surface.

oted jaw member being substantially within the range of 25° to 30°, and means resiliently urging the cam means into wedging engagement with said pivoted jaw member.

2. In a pipe tong, a handle, a plurality of relatively constrictable pipe-engaging jaws mounted thereon, means pivotally connecting at least one of the jaw members to the handle so that movement of the handle about its pivot tends to constrict said jaws, a plunger slidably mounted on the handle and having a cam surface adapted to wedgingly engage a cooperating surface on said pivoted jaw member, said cam surface being disposed at an angle of approximately 25° to 30° with respect to the longitudinal axis of the plunger and contacting the cam surface of said pivoted jaw member at a wedge angle of approximately 25° to 30°, and means resiliently urging the plunger into wedging engagement with said pivoted jaw member to yieldably maintain the jaw member in pipe-engaging position.

3. A pipe tong comprising a handle, a plurality of relatively constrictable pipe-engaging jaws mounted thereon, at least one of the jaw members being pivotally mounted on the handle so that movement of the handle about its pivot tends to constrict the jaws, spring-pressed plunger means mounted on the handle and having a cam surface adapted to engage the pivoted jaw with a wedging action, means connected to the plunger means for manually retracting the same, said plunger means having a surface at the end thereof extending substantially parallel to the longitudinal axis of the plunger means and adapted to engage the pivoted jaw to provide a positive lock preventing removal of the tong from the pipe except when the plunger means is manually retracted.

4. A pipe tong comprising a handle having a body rigid therewith, said body having a pair of oppositely disposed prongs forming a constantly-open pipe-receiving socket, an arcuate jaw pivoted to one of said prongs and having two bearing points for engaging the pipe, separated from each other circumferentially and engaging the pipe on opposite sides of a line drawn through the pivotal axis of the jaw and the center of the pipe, a pipe-engaging bit carried by the jaw at one of said bearing points, the opposite prong on the body having a smooth wedge face inclined so as to engage the pipe with a wedging

action when the handle is swung forward, spring-pressed plunger means mounted on the handle and having a cam surface adapted to wedgingly engage a cooperating surface on the jaw, the effective wedge angle between said cam surface on the cam means and the cooperating surface on said plunger being substantially within the range of 25° to 30°.

5. A pipe tong comprising a handle and a plurality of relatively constrictable pipe-engaging jaws mounted thereon, means pivotally connecting at least one of the jaw members to the handle so that movement of the handle about its pivot tends to constrict said jaws, and means yieldably maintaining the jaw member which is pivoted to the handle in pipe-engaging position comprising cam means mounted on the handle and having a cam surface wedgingly engaging a cooperating surface on said pivoted jaw member at a point on that side of the jaw pivot which is toward the pipe-receiving opening, the effective wedge angle between the cam surface on the cam means and the cooperating surface on said pivoted jaw member being substantially within the range of 25° to 30°, and means resiliently urging the cam means into wedging engagement with said pivoted member to yieldably maintain said pivoted jaw member in pipe-engaging position.
